UNITED STATES PATENT OFFICE.

BENJAMIN FRANKLIN KENDALL, OF ANDERSONVILLE, KENTUCKY.

BEE-HIVE.

SPECIFICATION forming part of Letters Patent No. 391,162, dated October 16, 1888.

Application filed March 27, 1888. Serial No. 268,643. (Model.)

To all whom it may concern:

Be it known that I, BENJAMIN FRANKLIN KENDALL, a citizen of the United States, residing at Andersonville, in the county of Meade 5 and State of Kentucky, have invented certain new and useful Improvements in Bee-Hives; and I do declare the following to be a full, clear, and exact description of the invention, such as will enable others skilled in the art to which it 10 appertains to make and use the same, reference being had to the accompanying drawings, and to the letters and figures of reference marked thereon, which form a part of this specification.

15 My invention relates to bee-hives; and its objects are, first, to arrange the hive and its compartments so as to permit the bees to work unobstructedly in filling the surplus comb-frames; second, to insure perfect ventilation; 20 third, to prevent the attack of foreign insects; fourth, to provide ease in handling and security to the operator, and, fifth, to procure the ready removal and replacement of the comb-racks. I attain these ends by the construction 25 hereinafter described, and illustrated in the drawings, in which—

Figure 1 is a vertical sectional view of the hive, taken through it from side to side, looking from the front toward the rear of the hive. 30 Fig. 2 is a vertical section on the line $x-x$ of Fig. 1, looking from the left-hand side of said figure toward the right thereof. Fig. 3 is a perspective view of the waste-drawer, and Fig. 4 is a similar view of the sliding frame carrying the brood-frames.

35 The same letters indicate corresponding parts in the several views.

A represents the brood-chamber of the hive, having an entrance, a , under which is an opening, b , for the passage of moths, and between the two is the alighting-board B for the bee entrance to brood-chamber.

C is a vertical sliding door working between two cleats, C' , (one of which is not shown on the drawings,) which can serve to close the bee-entrance a .

D is a hinged door having two guide end pieces, d , and formed to open outwardly. Supporting-blocks d' d'' are respectively secured 50 to the adjacent edges of the door D and its frame, the hinges d''' being between the same,

so that in opening said door it will be horizontally supported by reason of the block d' resting upon the rigid block d'' .

E is a door formed in the wall of the brood-chamber, and the wall also has a glass, e , between the door and said chamber, through which the interior can be inspected when desired.

F is the moth chamber, provided with a 60 swinging door, F' , to permit the egress of the waste-drawer F'' , which serves to catch the dirt from the hive and attract the moths by the luminous condition of its interior, owing to the passage of light through the screen f' .

To close the joints and prevent the hive from warping, cleats or strips a' are secured around the top of the brood-chamber, and similar strips, a'' , are secured around the bottom of the upper or surplus chamber for the same purpose. 70 An opening, g , normally closed by the pivoted door g' , is cut in the wall of the upper or surplus chamber, G , and is used to facilitate the injection of smoke when honey is to be removed.

The upper or surplus chamber, G , is provided 75 with a cap, G' , which is removable, and the front of the chamber has a sliding shutter, g' , that closes an opening, g'' , which is covered with glass, g'' , to permit inspection of the interior. The inside of the chamber G has cleats g'' formed to support the ends of honey section-frames H , underneath which is a wire screen, I , formed in the diaphragm separating the compartments G A , the latter being also perforated to form an opening, I' , (which affords 85 the only communication to the bees between the chambers A G , thus rendering access controllable by the operator,) covered by a sliding plate, I'' , working in a slot formed by the adjoining termini of the chambers G A , provided 90 with a handle, I'' , projecting outwardly, and under said screen I are suspended a number of honey brood-frames, K , on a removable frame, K' , that is formed to slide onto the transferring or hiving board after opening door D . A wire-cloth frame, L , is secured between the adjoining termini, constituting a diaphragm or floor, W , of the chambers A F under the sliding frame K' , and directly under said frame is arranged the waste-drawer F'' , provided with 100 opening f , covered by a wire screen, f' , to prevent egress of moths and admit light. The

sides f^2 are formed with perforations f^3 , through which moths pass from the opening b' into said drawer F' , as shown in Fig. 2, being attracted by light and by the scent of the honey and bee-waste.

The honey brood-frames K , suspended in the removable frame K' , are pivoted at one end, k' , to permit of their free ends opening outwardly, in the manner of a book-leaf.

10 The upper bars of the honey section-frames H , suspended in the surplus chamber of the hive, are placed close to each other to prevent bees from passing over the frames. This chamber holds about twenty-four pounds of honey.

15 The back of each frame is provided with tin keepers or stays h , to prevent the frame from bulging by the honey when placed in the frames, as shown in Figs. 1 and 2.

V is a knob on the drawer F' .

20 W represents the floor of the compartment A .

X X' represent a hook and eye attached, respectively, to the frame D and door F' , whereby the latter may be kept closed.

25 Y represents the ledges of the frame whereon the brood-frames K slide. There are provided notches in the lower rear bar of the sliding frame that serve to permit the bees to pass

around the rear of the sliding frame K' and enter the surplus honey-chamber G .

Z is a knob for the brood-frame K' .

The honey section-frames H are parts of the permanent hive and are intended to hold ordinary honey-sections, (the contents whereof may be consumed or sold, or the sections themselves sold.)

Having thus fully described my invention, what I claim is—

The bee-hive herein described, consisting, essentially, of three sections or compartments separated by wire screens I L , the lower compartment being provided with a door, F' , a moth-entrance, b' , and a removable moth-drawer having its end next to the door covered by a screening, f' , and its sides provided with openings f^3 , the central compartment having 45 a supporting-door, D , bee-passages F , and a sliding frame, K' , carrying pivoted brood-frames, as set forth.

In testimony whereof I affix my signature in presence of two witnesses.

BENJAMIN FRANKLIN KENDALL.
